(57) CLAIM

The ornamental design of a laser etched socket, illustrated substantially as shown and described.

DESCRIPTION

FIG. 1 is a perspective view of a laser etched socket embodying the design of the present invention, whereby the size indicia is defined by etching away a surface layer surrounding the size indicia so that the size indicia is distinguishable from the surrounding etched area; FIG. 2 is a front elevational view of the laser etched socket illustrated in FIG. 1;

FIG. 3 is a rear elevational view of the laser etched socket illustrated in FIG. 1;

FIG. 4 is a right side elevational view of the laser etched socket illustrated in FIG. 1;

FIG. 5 is a left side elevational view of the laser etched socket illustrated in FIG. 1;

FIG. 6 is a top view of the laser etched socket illustrated in FIG. 1; and,

FIG. 7 is a bottom view of the laser etched socket illustrated in FIG. 1.

The broken lines are for illustrative purposes and form no part of the claim.
